UNITED STATES PATENT OFFICE

1,985,001

INHALER

Harry M. Thometz, Oak Park, Ill.

Application July 1, 1933, Serial No. 678,577

4 Claims. (Cl. 128—200)

The present invention relates to an inhaler but more particularly to a novel and improved form of inhaler adapted to contain a porous material to be saturated with a proper volatile medicament through which air is drawn with the volatilized substance into the nostrils of the user.

The primary object of the present invention is to provide a novel and improved form of inhaler, which automatically closes after each use thereof, so as to prevent the evaporation of the volatile medicinal substance with which the device is charged.

15 A further object of the invention is to provide a novel and improved inhaler of the portable or pocket type form which can be concealed in the palm of one hand and manipulated or opened by the thumb of the same hand without making oneself or the device conspicuous.

20 A further object of the invention is to provide a novel and improved inhaler in which the outer casing is provided with internal longitudinally extending spaced apart ribs so as to reduce the friction resistance of and permit an internal 25 cylindrical casing which contains the medicament to reciprocate therein with perfect ease so that the action of the spring may automatically close and prevent the evaporation of the medicament.

30 These and other objects are accomplished by providing a construction and arrangement of the various parts in the manner hereinafter described and particularly pointed out in the appended claims.

25 Referring to the drawing:

Fig. 1 is an enlarged longitudinally cross sectional view of my improved form of inhaler showing the same in closed position;

Fig. 2 is a similar enlarged longitudinal cross sectional view showing the inhaler open and ready for use:

Fig. 3 is an enlarged side elevational view with a portion thereof broken away showing the construction and operation of the outside casing with respect to the internal cylinder.

Fig. 4 is a cross sectional view taken on the line 4-4 in Fig. 1.

Fig. 5 is a cross sectional view taken on the line 5—5 in Fig. 2;

50 Fig. 6 is a cross sectional view taken on the line 6—6 in Fig. 2;

Fig. 8 is a perspective view of the external
cylinder or casing.

55 cylinder or casing.

The invention in the present instance is primarily intended as a pocket inhaler in which a medicament or an inhalant remedy that has a sedative and soothing action on inflamed mucus membranes throughout the entire respiratory tract may be conveniently carried in the pocket or hand bag of a person for intermittent use so as to relieve congestion, check secretion and aid in the treatment of colds, hay fever, hyperesthetic rhinitis, sinus infections, nasal congestion from whatever cause, asthma and bronchitis. 5 10

In illustrating one form of my invention I have shown the same as comprising an outer cylindrical casing generally indicated by the reference character 10. This casing 10 is provided with a closed bottom 11 and an opening at the upper end thereof. The upper portion of the casing 10 is provided with a reduced portion, as shown at 12, forming a shoulder 13. This reduced portion 12 telescopically receives in frictional engagement therewith, a cap or nozzle 14. Located on one side of the casing 10 and extending vertically through the reduced portion 12 and extending into the casing proper a short distance below the top thereof, is a slot 15. The cap 14 is provided with an internal longitudinally extending rib 22 which is adapted to seat in the complementary slot 15 of the casing 10. Located within the cylindrical casing 10, at equally spaced apart distances within the internal circumference thereof, are three spaced apart inwardly projecting ribs 16 which project inwardly with respect to the diameter of the inside of the casing 10 a few thousandths of an

inch, but for the purpose of illustration, are exaggerated in this drawing. The purpose of these inwardly projecting ribs 16 is to reduce the frictional resistance of the reciprocating internal container hereinafter described. Located adjacent the lower portion of the container 10 and extending through each of the ribs 16 are spaced apart apertures 17. Reciprocally mounted within the casing 10 is a cylindrical container, generally indicated by the reference character 18. The lower end of this cylindrical casing 18 is opened while the upper end is provided with a top, generally indicated by the reference character 19, and is also provided with arcuate spaced openings of which there are four in number and generally indicated by the reference character 20. This top portion 19 forms a substantially disc shaped flat surface, as shown at 21, and is of sufficient diameter to cover the opening 22 located in the

nozzle 14, as clearly shown in Fig. 1 of the drawing. Formed integrally with the internal container 18 and extending laterally with respect thereto is a laterally projecting lug 23 which is adapted to extend through the slot 15 in the outer casing 10 as clearly shown in Figs. 1, 2 and 3 of the drawing. Located in the lower portion of the inner cylindrical casing 18 and adapted to register with the perforation 17 in the casing 10 when in one position, are spaced apart apertures 24. The inner cylindrical casing 18 is automatically pressed upwardly with respect to the outer casing 10 by means of a helically coiled spring 25 which has its large diameter engaging the lower edge and opened end of the inner casing 18 and its lower end and small diameter seated on an upwardly projecting boss 26 formed in the bottom 11 of the outer casing. Loosely contained within the inner cylindrical casing 18 is an unmedicated dry porous filler 28 which is adapted to be saturated with any suitable medicament which will relieve the conditions previously referred to of the respiratory tract.

The operation of my improved inhaler is as follows: Let us assume that the inhaler is in the closed position shown in Fig. 1 and that the operator is desirous of charging or saturating the dry porous filler 28 with a medicament. The liquid is poured into the opening 22 in the cap or nozzle 14, which serves as a measure and after the aperture 22 has been filled, the thumb may actuate the lug 23, so as to move it downwardly in a slot 15 thereby moving the inner cylindrical casing 18 with respect to the outer casing 10 and permit the liquid to pass through the openings 20 in the inner casing to saturate the porous dry filler 28.

In the use of my improved inhaler, the device is sufficiently small and compact to fit into the palm of a hand of the user and arranged so that the thumb of the same hand may manipulate the lug 23 to move the internal container 18 downwardly with respect to the outer casing 10 against the pressure of the spring 26. When moved from the position shown in Fig. 1 to that shown in Fig. 2, the inhalant vapors may be drawn upwardly in the manner indicated by the arrows, through the aligned apertures 17 and 24 in the respective outside and inside casings in response to the inspiratory action of the nostrils when the inhaler is placed in position with the nozzle or cap 14 at the entrance to the nostril. It will be readily observed from the above description and illustration of the drawing, that by providing the three internal ribs on the outer casing 10, the frictional resistance to the action of the spring and the manipulation of the lug 23 is reduced to a minimum. That upon releasing the lug 23, the device automatically closes thus preventing the evaporation of the inhalant contained in the inhaler.

From the above construction it will be readily seen that I have provided a simple, compact and automatically operable inhaler which can be conveniently carried about in a pocket or hand bag and which also can be concealed within the palm of a hand without making oneself or the device conspicuous.

While in the above specification I have described one embodiment which my invention may assume in practice, it will of course be understood the same is capable of modification and that modification may be made without de-

parting from the spirit and scope of the invention as expressed in the following claims.

What I claim as my invention and desire to secure by Letters Patent is:

1. An inhaler comprising an outer cylindrical casing, longitudinally spaced apart ribs extending inwardly from the inner surface of said casing, a reciprocable cylindrical casing within said outer casing and adapted to engage said ribs, said outer casing having a longitudinal slot adjacent the upper end thereof, a lug carried by said inner casing and extending through said slot for reciprocating said inner casing with respect to said outer casing, a nozzle secured to the upper end of said outer casing having an aperture extending therethrough, a closure portion formed at the upper end of said inner casing and adapted to close the aperture in said nozzle, there being spaced apart apertures in said outer casing extending through the ribs thereof, and a compression spring located in the bottom of said outside casing and engageable with the lower end of said internal casing for normally actuating the inner casing upwardly with respect to the outer casing, there being spaced apart apertures in said inner casing adapted to register in alignment with the apertures in said outer casing when the inner casing is depressed with respect to the outer casing.

2. An inhaler adapted to be operated by one hand comprising a cylindrical outer casing having a bottom formed integrally therewith and opened at the top thereof, a reciprocable inner casing mounted within said outer casing, said outer casing having a longitudinal slot in the wall thereof, a lug formed on said inner casing and projecting through said slot for actuating said inner casing with respect to said outer casing, spaced apart longitudinally extending ribs formed in the inner surface of said inner casing forming the frictional contact between said casings, a cap frictionally secured to the upper end of said outer casing having an aperture therein, a closure portion formed integrally with the upper part of said inner casing adapted to cover the opening in said cap, a plurality of spaced apart apertures located in the lower end of said outer casing and extending through said ribs, there being a plurality of spaced apertures in the lower portion of said inner casing adapted to register in alignment with the apertures in said outer casing when said inner casing assumes a predetermined position with respect to said outer casing, and a spring mounted between said outer casing and said inner casing for automatically actuating said inner casing upwardly with respect to said outer casing and closing the aperture in said cap.

3. An inhaler adapted to be concealed in the palm of one hand and adapted to be manipulated by the thumb of the same hand, comprising a cylindrical casing having a bottom and a reduced upper portion, a longitudinal slot formed adjacent the upper end of said casing, inwardly extending ribs formed on the inner surface of said casing, a reciprocable cylindrical casing mounted within said first named casing and adapted to frictionally engage said ribs, a cap having an aperture therein frictionally secured to the reduced portion of said outer casing, said inner casing having a central closure portion with apertures therearound with the closure portions adapted to cover the aperture in said

cap, there being a plurality of spaced apart apertures located in the lower portion of said outer casing and extending through said ribs, there being a plurality of apertures in the lower portion of said inner casing adapted to be moved into registering alignment with the apertures in said outer casing when the inner casing is depressed with respect to the outer casing, a spring for automatically moving said inner casing upwardly with respect to said outer casing for closing the aperture in said cap, and a laterally projecting lug formed integrally with said inner casing and extending through the longitudinal slot in said outer casing whereby said inner casing may be manipulated with respect to said outer casing for withdrawing the inhalant therein.

4. A pocket inhaler adapted to be concealed in the palm of the hand comprising an outer cylindrical casing having a bottom therein and upper opened end, a reduced portion formed at the upper end, a longitudinal slot located in the upper end of said casing, said casing having internal longitudinally extending ribs formed on the inner surface thereof, a reciprocable inner cylindrical casing adapted to frictionally engage said ribs, a cap secured to the upper end of said outside casing and frictionally secured to

the reduced portion thereof, said cap having an aperture therein, a closure portion formed at the upper end of said internal casing having apertures therearound and arranged so as to cover the aperture in said cap, a spring mounted between the lower ends of each of said casings for normally urging said inner casing upwardly with respect to said outside casing for closing the aperture in said cap, there being a plurality of circumferentially arranged apertures at the lower portions of each of the casings adapted to register when the inner casing is depressed with respect to the outer casing, the apertures in the outer casing extending through said ribs, a helically coiled spring having one of its ends engaging a boss in the bottom of said outer casing and the other of its ends engaging the lower edge of said inner casing for normally urging said inner casing upwardly with respect to said outer casing for closing the opening in said cap, and a laterally projecting lug extending through said slot in the outer casing whereby said inner casing may be moved downwardly by the thumb of the hand in which said inhaler is supported so that the inhalant contained in the inhaler may be withdrawn by the respiratory action of the nostrils.
